UNITED STATES PATENT OFFICE.

ORMAH R. MITCHELL, OF OAK PARK, ILLINOIS, ASSIGNOR TO AMERICAN STEEL
FOUNDRIES, OF CHICAGO, ILLINOIS, A CORPORATION OF NEW JERSEY.

SUPPORTING MECHANISM FOR BRAKES.

1,302,575.

Specification of Letters Patent.

Patented May 6, 1919.

Application filed February 13, 1918. Serial No. 216,941.

To all whom it may concern:

Be it known that I, ORMAH R. MITCHELL, a citizen of the United States, and resident of Oak Park, in the county of Cook and 5 State of Illinois, have invented certain new and useful Improvements in Supporting Mechanism for Brakes, of which the following is a specification.

This invention relates to supporting mechanism for brakes.

One of the objects of this invention is to adjustably support brake beams in an improved manner whereby the same may be leveled in accordance with operating conditions.

Another object is to provide a simple and effective leveling device for brake beams adapted to meet the various requirements for successful commercial operation.

Generally speaking, these and other objects are accomplished by providing, in combination, a brake beam, a safety bar therefor, a member operatively connected with the safety bar and beam for supporting the latter, and serrated means whereby said member may be adjusted for leveling the brake beam.

The invention is illustrated on the accompanying sheet of drawings, in which—

30 Figure 1 is a fragmentary side elevation of a railway car truck embodying my invention;

Fig. 2 is a fragmentary enlarged side elevation, parts being in section, of my improved leveling device and its associated parts;

Fig. 3 is a sectional view taken in the plane of line 3—3 of Fig. 2;

Fig. 4 is an enlarged side elevation, parts 40 being in section, of a modification of the arrangement shown in Figs. 1 and 2; and,

Fig. 5 is a sectional view taken in the plane of line 5—5 of Fig. 4.

The various novel features of my invention will be apparent from the following description and drawings and will be particularly pointed out in the appended claims.

I have disclosed my invention in connection with a railway car truck, including a 50 spring plank 10, to which are secured hangers 11 for supporting a horizontally arranged safety bar 12, the outer ends of which underlie brake beams 13 for preventing the latter from accidentally falling to the tracks 55 in the event that they become detached from

their normal hangings. In order to prevent the tension rods 14 of the brake beams from sagging, I have provided members 15, preferably of resilient material, which preferably are in the form of a loop having one 60 end 16 thereof slipped over the safety bar, while the other end 17 is adjustably connected with respect to the safety bar. An intermediate inclined portion 18 of the leveling member 15 slidably receives the tension 65 member 14 of the brake beam, or, if desired, a head 19 mounted on the tension member may slide on the intermediate portion 18 of the leveling member 15. The end 70 of the leveling member 15 is secured to the safety bar and the safety bar secured in place with respect to the hangers 11 by spring clips 20, which are secured to the sides of the safety bar adjacent the hangers 11.

In order to adjust the brake beam for proper leveling thereof, I have shown, reference being had to Figs. 1 and 2, one portion 17 of the resilient leveling device 15 with serrations or teeth 21, which coöperate with corresponding serrations or teeth 22 formed on the inside of a band 23 embracing the serrated end 17 of the leveling member 15, and also the end of the safety bar, the member 23 preferably being secured to the 85 safety bar by a removable pin 24 normally held in place by a cotter pin 25.

From this arrangement it is apparent that if it is desired to raise or lower the front part or tension rod of the brake beam, the 90 same may be accomplished by withdrawing the pin 24 and adjusting the member 15 in the desired direction, whereupon the teeth 22 of the band 23 may be brought into locking association with the teeth or serrations 95 21 of the member 15, and the band again secured to the safety bar by means of the pin 24. In this way it is a simple matter to adjust the leveling device for leveling the brake beam, and at the same time when the 100 locking band 23 is once set in position, the parts are positively locked.

By referring to Fig. 4, it will be noted that I have shown a modification of my invention wherein the outer end of the safety bar 26 is provided with teeth or serrations 27, which coöperate with the teeth or serrations 28 on the inside edge of the downwardly extending portion 29 of the spring leveling member 30, the brake tension mem- 110

ber 31 being slidably supported upon the inclined portion 32 of the leveling member 30. It will be noted also that the leveling member 30 has but the single end 29 engaging 5 with the safety bar 26. The band 33 which embraces the serrated end 29 of the leveling member 30 in this case is not serrated, the function of the band 33 in this case being merely to hold the serrated portions of the 10 leveling member 30 and of the bar in normal locking position, and for permitting their release when it is desired to adjust the vertical position of the beam.

It is my intention to cover all modifications of the invention falling within the spirit and scope of the following claims.

I claim:

1. In combination, a brake beam, a safety member therefor, a member operatively connected with the safety member and beam for supporting the latter, and serrated means whereby said member may be adjusted for leveling the brake beam.

2. In combination, a brake beam, a safety 25 bar therefor, a toothed leveling member connected to the safety bar and operatively connected to the beam for slidably supporting the latter, and coöperating means whereby the leveling member may be adjusted and 30 locked in adjusted position.

3. In combination, a brake beam, a safety member underlying the same, a support for the beam, and a coöperating toothed member for releasably locking said support to the safety member.

4. In combination, a brake beam, a safety bar underlying the same, a support for the beam, and a coöperating toothed member for adjustably and releasably locking said support to the safety bar.

5. In combination, a brake beam, a safety bar underlying the same, a member for slidably supporting said beam, said member having a toothed portion, and a member embracing said toothed member and bar for 45 securing the same together.

6. In combination, a brake beam, a safety bar therefor, a member for slidably supporting the brake beam and having a toothed portion, and a toothed member 50 associated with the toothed portion of said supporting member operatively connected to the safety bar for holding the supporting member in adjusted position.

Signed at Chicago, Illinois, this 25th day 55 of January, 1918.

ORMAII R. MITCHELL.
